UNITED STATES PATENT OFFICE.

FRANK LANE LEVY, OF DULUTH, MINNESOTA.

CUTTER.

SPECIFICATION forming part of Letters Patent No. 701,061, dated May 27, 1902.

Application filed October 16, 1901. Serial No. 78,830. (No model.)

To all whom it may concern:

Be it known that I, FRANK LANE LEVY, a citizen of the United States, and a resident of Duluth, in the county of St. Louis and State of Minnesota, have invented new and useful Improvements in Cutters, of which the following is a full, clear, and exact description.

This invention relates to a device for cutting cloth in strips. It is particularly adapted to use by dressmakers for cutting material to form ruffles and like work.

This specification is a specific description of one form of my invention, while the claim is a definition of its actual scope.

Reference is to be had to the accompanying drawings, forming a part of this specification, in which similar characters of reference indicate corresponding parts in all the figures.

Figure 1 is a bottom plan view of the invention. Fig. 2 is a front elevation thereof, and Fig. 3 is a detail of one of the cutters and its pin.

The body of the device is formed of a transversely-extended preferably metallic bar *a*. This bar is formed with vertically-disposed openings loosely receiving pins *b*, which are arranged side by side in transverse alinement and carry at their lower ends rotary cutters *c*. For adjustably holding the pins *b* in the bar *a* I provide set-screws *d*, which work in the bar and are adapted to bind, respectively, against the pins.

e indicates a handle which is attached to the bar *a* by means of a shank *f* and a bow-shaped brace *g*.

With this device cloth may be cut in strips of any width desired. The width of the strip may be regulated by raising or lowering the pins *b*. If it be desired, all of the cutters may be allowed to act, and any number of them 40 may be raised out of action by manipulating the thumb-screws *b*.

The device is used by drawing the knives or cutters over the cloth, as will be clearly understood from Fig. 2, which shows the cutter in operative position.

Having thus described my invention, I claim as new and desire to secure by Letters Patent—

A cutter, comprising a bar forming a body 50 portion, a handle for the bar, pins mounted loosely on the bar and extending transversely thereof, said pins being of uniform diameter to permit their free adjustment in the bar in direction longitudinally of the axis of pins, 55 and the pins being of length considerably greater than the width of the bar, set-screws working in the bar and respectively engaging the pins adjustably to hold them, and cutting-tools carried by the lower ends of the 60 pins.

In testimony whereof I have signed my name to this specification in the presence of two subscribing witnesses.

FRANK LANE LEVY.
